RALPH H. UPSON, OF DETROIT, MICHIGAN.

KITE BALLOON.

Application filed July 3, 1928. Serial No. 120,265.

This invention relates to balloons of the type known as kite balloons and has for its object the provision of means on such a kite balloon that will better assure steadiness or stability when in the air, and particularly under the varying conditions of wind and when launching or hauling down and landing the kite balloon.

Among the particular objects are the provision of fins on such kite balloon of a special form and arranged and cooperating with the rest of the balloon in the manner hereinafter more fully described.

A particular embodiment of my invention is shown in the accompanying drawings, in which:

Fig. I is a perspective view of a kite balloon containing the inventions in a particular form.

Fig. I^a is a fragmentary section on an enlarged scale of one form of air scoop for fins.

Fig. II is a rear elevation.

Fig. III is a front elevation.

Fig. IV is a cross-section at right angles to the axis of the balloon at a point passing through the fins.

Fig. V is a fragmentary enlarged view of a fin end air-scoop and valve.

Fig. VI is a fragmentary view showing a relief valve for the balloon body proper.

Fig. VII is a fragmentary view of part of the balloon body and through the medial plane of a fin.

Fig. VIII is a cross-section on enlarged scale, on the line 8—8, Fig. VII.

This embodiment of my invention has a kite balloon body 1 which is usually a fabric bag adapted to be inflated with buoyant gas, and having in its forward end a relief valve 2 which will automatically relieve any excess pressure beyond a predetermined amount. On the interior is a balloon diaphragm 3 fastened along the sides below the middle and of surplus material permitting the diaphragm to swell due to air pressure on the underside, and thereby transmit pressure to the gas above the diaphragm forcing the gas pressure to distend the balloon body proper, and also to distend the fins adapted to be inflated by gas and having direct connection with the gas in the main body portion.

The fins in the preferred form, consist of fins 4—4 conical or multi-conical in shape,

with an axis projecting radially from the surface of the body 1 and each comprising a plurality of generally cone-shape sections 4^a, each with its large base secured to the surface of the balloon proper and each of the sections 4^a being separated by diaphragms 5—5 peppered with holes 5^a so that gas may move from each of the cone-shape compartments into the adjacent ones, and keep all of the fins substantially uniformly inflated from the base where it connects with the body of the balloon to the ends of the fin. Where the fin joins the bag 1 the envelope of the bag is perforated or peppered with holes 6 so as to allow access of the gas from the bag into the fin and through the entire extent of the fin from the bag-envelope to the tip of the fin. It will thus be seen that the gas pressure in the main envelope is also maintained throughout the fin, and thereby upon inflation of the kite balloon these fins are also inflated and stiffened and form effective stabilizing or steadyng protuberances throughout their length to their tip, avoiding any chance of these fins becoming flabby irrespective of wind conditions, and thus assuring their effectiveness when launching, as well as landing or maintaining the kite balloon in the air.

The particular form of the fins is obtained by making the fin envelope substantially as shown in Figs. VII and VIII, wherein the several parts or sections are substantially conical with a wide base at the bag surface and converge to a common apex 7, but with a substantial portion of the apex cut off to form the outer edge of the fin substantially parallel with the axis of the balloon and of an appreciable extent, so that the outer edge may be formed into a scoop 8, in the case of other fins 9—9 which are inflated by air—as hereinafter described. This fin fabric is fashioned to give the form illustrated, and therefore an envelope with fairly flat surfaces longitudinally of the balloon, is restrained by the partitions 5—5 holding the opposite walls together so that upon the inflation of the several compartments the fin in its distended condition approximates a plurality of conical surfaces, that is a generally flat-sided conical form.

While the fins 4—4 inflated with gas are set at forty-five degrees above the horizontal, they provide in a captive or kite balloon,

which is slightly inclined with its axis pointing slightly upward, a form that gives lift by resistance to the wind, and thereby materially helps in stabilizing, which would not be the case if these fins were in a normally vertical position. By having the fins 9—9 each forty-five degrees below the horizontal, a similar result is obtained, so that four of such fins extending from the rear half of the kite balloon, add greatly to the steadiness or stability and materially prevent pitching.

In the case of the lower two fins 9—9, the scoop 8 has a duct 8^a separated from each of the sections of the fin by diaphragms 10—10, which are perforated or peppered with holes in a manner that will admit the air fairly uniformly into each of the sections, while the peppered partitions 5—5 furthermore assure the maintenance of like pressure throughout the sections of the fin. From the base of these air inflated fins a vent 11 through the bag-envelope permits flow into the balloonet air space, that is below or underneath the diaphragm 3. At the same time the balloonet has its pressure maintained by air flowing into the forward scoop 12 which is always in an unobstructed position to resist the wind, so that with the increase of wind requiring the stiffening of the fins to best function, such increased inflation is caused by the increased pressure of the wind. I may also add a scoop near the base of each air-inflated fin, as shown dotted at 13, Fig. I, and in enlarged scale in Fig. I^a where the scoop is secured to the outer surface of the balloon-bag proper and extends to the base of the conical front edge section of fin 9 with a suitable perforated wall admitting air, and a flap 15 so formed that internal pressure presses a valve flap against the perforations thereby preventing air from flowing out.

As in these kite balloons changes of temperature or operation may result in certain altitudes in an expansion, or, in any event, an excess pressure in the gas bags, I provide the blow-off or relief valve 2 consisting of valve disc 2^a held normal by spring 2^b to a yoke 2^c. However, I locate this blow-off valve well forward, and preferably just under the nose of the balloon body so that the outward-opening type shown is subject to the internal pressure but also to the wind pressure, and thereby the harder the wind against the outside the higher will be the internal blow-off pressure, thus with high winds still better insuring the stiffness of the balloon envelope and in particular also the stiffness of the fins.

It will be seen that the forty-five degrees position of the air-inflated fins makes it possible to have the connection 11 with the balloonet so high on the side that they are normally above the air level in the balloonet, with the diaphragm 3 covering the vent 11. Thus

the small scoops at the tip of the fins assure the inflation of the fins while the flap 8^b prevents the air from flowing out again, and it must force its way against the diaphragm 3 into the balloonet, when the diaphragm acts as a valve, and also thus increasing the pressure in the balloonet, but in the main and large scoop 12 there is no check-valve, so that balloonet pressure is automatically balanced in proportion to the wind on the area of the main scoop cross-section.

The advantages of the form of fins and arrangement will be realized in view of the greater stability and better balance which they give to the kite balloon, under which conditions the observation car 16 can be relatively close-coupled to the supporting balloon body and close to the mooring and communication cable. There is more aerodynamic lift and the various forces are so distributed that the balloon tends to keep an almost constant position in the air for a wide range of wind speeds. The importance of this is obvious, particularly when considering one of the prime uses, namely, for artillery observation. This arrangement of the lower fins assures their keeping their air under normal conditions for an appreciable length of time even if the wind should momentarily die out, which is a condition that is practically obtained in naval maneuvers where the balloon is being towed alternately with and against the wind. The gas valve arrangement, furthermore, permits a reasonably low blow-off pressure and a high factor of safety for normal conditions, but at the same time it prevents disastrous cupping of the nose and the loss of gas under the effect of unusually strong winds or in the case of gusts, which are conditions that are always likely to occur. By the arrangement for inflation of the fins, their stiffness is maintained with the advantage of the fin tip scoops in a position of free-flowing air, and when desired having the fin base air supply from scoops well located when full effect of air currents is assured. These conditions with the generally flattened shape of the fin and their position generally in planes forty-five degrees from the horizontal and vertical, provide the very advantageous steadyng or stabilizing to resist yawing or pitching of the balloon, and thereby an almost constant position to the great advantage of the operations of the observers carried by the balloon.

The main gas bag is made of the usual fabric material so that it may be deflated when not in use and readily transported, but for certain purposes any other form of material may be used. The inflatable and therefore collapsible fins and collapsible main bag, however, serve the most essential purposes of the kite balloon, providing the stiff- 130

ness in all essential parts when in captive flight and occupying the smallest space when deflated, particularly desirable for stowing on shipboard when not in use.

5 For certain purposes and under certain conditions I may inflate all of the four fins with gas, and for other purposes I may use air inflation for the upper fins with the same advantages due to the form and the 10 arrangement of tip scoop and valve and connections with the balloonet, as hereinbefore described with reference to the lower fins, air-inflated, as illustrated and described, with such changes as necessary to connect the air 15 space in the upper fins with the balloonet or with the lower fins as by air pipes.

In the preferred form the main gas bag is elongated with a substantially circular cross-section, with a fineness of about two and a half 20 to three times the length to the maximum diameter, with a rounded nose and converging from the maximum diameter forward of the middle to the rounded stern, and the fins are 25 as shown placed along meridian lines of the main bag surface back of the middle but not extending to the rear. The flattened conical shape of the fins is preferably as shown, a plurality of connected conical surfaces produced by the diaphragms extending outwardly from 30 the base and converging toward the tip which restrain the lateral walls so that the inflation of each compartment or section takes the desired form of longitudinally flattened outward scolloped or fluted surfaces, with a relatively 35 large base and tapered to a fairly thin edge giving the very advantageous form that assures stiffness and maintains its predetermined position with relation to the balloon body surface.

40 Many variations may be made from the particular embodiments of my invention herein particularly illustrated and described, without departing from my invention,—but what I claim and desire to secure by Letters Patent 45 is:

1. A kite balloon having a main elongated body portion inflated with buoyant gas, a balloonet and a main air scoop therefor, a plurality of inflatable fins maintained radially 50 from the balloon surface in a wedge shape with their bases attached to the main body, and with walls held in shape by direct internal pressure extending wedge-shaped to the fin tip.

55 2. A kite balloon having a plurality of fins each consisting of generally wedge shaped envelopes with the larger end or base secured to the balloon envelope and with the wedge shaped walls converging radially outward toward a common apex with means providing direct internal pressure against the inner surface of the walls to counteract aerodynamic outside pressure on said fins.

60 3. A kite balloon fin having a generally flattened conical form of envelope extending ra-

dially from the kite balloon main gas envelope and radial partitions holding said envelope to said conical form in conjunction with internal pressure.

4. A kite balloon having two wedge formed 70 fin envelopes extending radially outward from the main balloon body and having radial internal wall interconnections and a free vent at their base for flow of the buoyant gas of the main body.

5. A kite balloon having two wedge formed 75 inflatable fins extending from below the middle radially outward from the main balloon body, and having means for maintaining air pressure against the inner surface of the 80 outer walls of the fins to stiffly inflate them.

6. In a kite balloon having a gas-bag and balloonet, an inflatable fin with walls extending straight radially from the bag-envelope, 85 inflatable uniformly from its base connection to its tip, and having near its tip an air scoop and a check-valve therefor and at its base an air connection to the balloonet.

7. In a kite balloon an inflatable fin having 90 a generally flattened-cone shape with its base secured to the main gas bag and outwardly converging with compartments extending from the base to the tip, radial partitions interconnecting the flattened sides and intercommunication between all parts providing 95 a free-flow of gas or air from the base to the tip.

8. In a kite balloon having a main body for 100 gas inflation, a balloonet, a blow-off valve in close proximity to the nose of the main body, envelopes adapted to be inflated to form stiff fins, and unchecked air-scoops for the balloonet and fins.

9. A kite balloon having an elongated gas 105 envelope of substantially circular cross-section, a plurality of fins extending radially from the envelope back of the middle, an outwardly-opening gas blow-off valve near the nose of the envelope in a position where in normal use of the kite balloon the outer surface of the valve will be subject to direct wind pressure.

10. A kite balloon having an elongated gas 110 bag and four inflatable fins extending radially along meridian lines substantially forty-five degrees from the horizontal and vertical planes through the axis of the gas bag.

11. A kite balloon having an elongated gas 115 bag, a balloonet along part of the bottom, two gas inflated fins extending radially about forty-five degrees above the horizontal plane of the axis of the balloon, and two radial fins adapted for air inflation extending generally in a plane about forty-five degrees below the horizontal from the rear half portion of 120 the gas bag.

12. A kite balloon comprising a main elongated gas container and a plurality of inflated fins of a flattened conical shape attached to the gas container along meridian lines, in- 125

- ternal radial means to restrict the lateral fin surfaces to predetermined size when inflated, and means for maintaining the inflation of the fins.
13. In a kite balloon of the character described, a plurality of air-inflatable fins each independently inflatable and each consisting of a flattened envelope with a large base attached along meridian lines of the main balloon envelope and tapering outwardly to a smaller section, stiffening diaphragms in each fin extending from the base outwardly and restricting the sides of the envelope when inflated to the predetermined flattened shape, and interior air vents to permit substantially uniform air pressure throughout the fin.
14. A kite balloon of the character de-

scribed having a plurality of independent fins formed of an inflatable envelope with longitudinally flattened sides held to form by internal wall connections, an air scoop and an inwardly-opening check valve near the tip of each fin, an air scoop on the outer side of the main gas envelope and leading to an inwardly-opening check valve at the base of each fin where it meets the main gas envelope, and an uncheck vent from the base of the fin to the ballonet in proximity to the connection of the ballonet diaphragm with the interior of the main gas bag.

In testimony whereof, I have signed my name to this application this 22 day of May, 1926.

RALPH H. UPSON.
